(57) CLAIM

The ornamental design for a set of mats, as shown and described.

DESCRIPTION

FIG. 1 is a perspective view of a set of mats, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1; and,

FIG. 10 is an enlarged view of portion of FIG. 2.

The broken line showing of the set of mats is for the purpose of illustrating article and forms no part of the claimed design.
